UNITED STATES PATENT OFFICE.

FRIEDRICH STROHL, OF RUMPENHEIM-ON-THE-MAIN, GERMANY, ASSIGNOR TO C. A. NEUBECKER, OF OFFENBACH-ON-THE-MAIN, GERMANY.

CASK-HOOPING MACHINE.

1,155,767.

Specification of Letters Patent.

Patented Oct. 5, 1915.

Application filed May 21, 1915. Serial No. 29,629.

To all whom it may concern:

Be it known that I, FRIEDRICH STROHL, a subject of the Emperor of Germany, and resident of Rumpenheim-on-the-Main, in the 5 Grand Duchy of Hesse, Germany, have invented a new and useful Improvement in Cask-Hooping Machines, of which the following is a specification.

In machines heretofore used for hooping 10 casks it was necessary for the workman who operated the machine, to regulate the pressure on the hoops according to the size of the cask being hooped. This was a great disadvantage because if excessive pressure 15 was used, the cask would be squeezed out of shape and sometimes the hoops would be broken. Also in mechanically driven machines of this character, a predetermined regulation of the pressure on the hoops was 20 not possible and accordingly the successful operation of the machine depended entirely upon the workman's ability to accurately regulate the pressure to the various sizes of 25 casks to be hooped. In hydraulic driven machines for hooping casks, the pressure on the hoop is accurately shown by the manometer. But in machines of this character it is necessary for the workman to see that 30 greater pressure is used on the larger casks and that greater pressure is applied to the end hoops than the middle hoops and since the machine operates rapidly it requires a very high degree of speed and careful attention on the part of the man operating it. 35 In order to make this operator's work a little less difficult, a smaller hydraulic pipe was used so that the pressure would rise slowly, but it was found that this diminished the efficiency of the machine. The efficiency 40 of all these known machines is therefore dependent upon the workman, that is, upon his ability, his knowledge, and the interest which he has in his work and in his machine. Naturally these are very uncertain 45 factors, and it is the purpose of this invention to avoid this uncertainty.

In the accompanying drawings, Figure 1 is a side view partly in section, of a hydraulic cask hooping machine. Figs. 2 and 3 are detail views thereof. Fig. 4 is a modification of one of the parts of the machine. Fig. 5 is another modification of the same parts, and Fig. 6 is a side view partly in

section, of a mechanically driven cask hooping machine.

In the machine shown in Figs. 1, 2 and 3, the regulation of the machine is effected by a D slide valve 1. In the position shown in Fig. 1, the pressure fluid passes from the pipe 2, through the passage 3 and the pipes 4 and 5 into the cylinders 6 and 7, under the pistons 8 and 9. The pressure plates 10 and 11, with the pressure claws 12 and 13, approach each other at the slow speed of the pressure fluid as long as the claws push 65 against the hoop.

The auxiliary valve 15 is connected with the pipe 5, through the pipe 14 and with the cylinder 17 through the pipes 16. In the cylinder 17 is located a piston 18 whose upper end 19 contacts with the slide valve rod 20. The auxiliary valve 15 is operated through the medium of a lever 21, the weight 22 and the rod 23 on which all the weight plates 24 to 29 hang, when the pressure plate 11 is in its lowest position, that is, when the pressure plates 10 and 11 are the greatest distance from each other. On the end pressure plate 11, two rods 30, 31, are attached, on the lower ends of which rings 32, to 37 are screwed with lock nuts. In the plates 24-29, bores or holes are arranged so that the diameter of the bore of each plate is greater than that of the one above it and smaller than that of the one 85 below it, as shown in Figs. 2 and 3. The position of the rings 32-37 is so arranged that when the pressure plates 10 and 11 have approached one another as near as possible, all the weight plates 24-29 are removed from the rod 23, as shown in Fig. 2.

When the hoops of the largest casks are pressed, as shown in the drawings, the fluid pressure rises to its maximum height, and only at this pressure is the auxiliary valve 95 15 opened. When this takes place, the pressure fluid enters the pipe 16, lifts the piston 18 and the rod 20, and shifts the slide valve 1 to such a position that it shuts off the passage 3 from the fluid inlet pipe 2. When this 100 has taken place, the pistons 8 and 9 automatically stop and further pressure on the hoop ceases. If the middle hoops of the same cask are now to be pressed, the plates 10 and 11 must approach one another and 105 in doing so the rod 23 is relieved from the

weight plates 24—29. In this position the valve 15 is lifted by a less fluid pressure which passes through the pipe 16 and cylinder 17, and shifts the slide valve 1, thus 5 stopping the machine.

The piston 18 is acted upon by a spiral spring 39, which is strong enough to overcome the friction of the stuffing-box of the piston and keeps the piston from rising during the time when the passage 3 is opened to the waste pipe 42. The waste fluid then passes from the pipe 16, through the port 40 and the check valve 41. The cross section of the piston 18 is such that the minimum pressure of the fluid is sufficient to raise it and thus operate the slide valve 1.

In the form shown in Fig. 1, the lever 21 of the valve 15 is operated intermittently, but this can be avoided by using the modification shown in Fig. 4.

In Fig. 4, the chain 44 is fastened to the pressure plate 11 and to the end of the lever 21, and hangs as a loop when the plate 11 is in its lowest position. When the plate 11 rises, the loop of the chain becomes smaller, thus gradually relieving the lever 21 of its weight in a manner which is clearly apparent from the drawings.

In the modification shown in Fig. 5, a vessel 45, which is filled with a suitable fluid, is attached to the end of the lever 21, and communicates with another vessel 47, which hangs from a lever connected with the plate 11. With this arrangement, when the plate 11 rises, the vessel 47 descends by reason of its lever arrangement so that according to its position, the fluid in the vessel 45 flows into the vessel 47, thus gradually relieving the lever 21 of its weight. Such a regulating device can also be used in a mechanically driven cask hooping machine in which one plate only is placed on a hydraulic piston, as shown in Fig. 6. Here the piston 48 of the pressure plate 49 lies in a hydraulic cylinder 50, which is connected with the cylinder 51. The piston 52 is controlled by the position of the pressure plate 53, in such a manner that with the increasing size of the casks, more weights 56 are laid on the piston 52 by means of the ropes 54, 55. As soon as the fluid pressure determined by the size of the

cask, that is, by the position of the hoop, is reached, the piston 52 rises and shifts by means of the bell-crank lever 57, the axis 58, with its friction wheels 59, so that further action on the hoop ceases at once.

From the preceding description it is evident that independently of the workman, the pressure on the hoops is completely and automatically regulated according to the size of the casks. Furthermore, the end hoops are pressed with greater pressure than the middle hoops. It will be seen, therefore, that it will not be necessary to have an operator attending the machine because the movement of the regulating device occurs automatically from start to finish.

What I claim is:

1. In a cask hooping machine, the combination of a pressure regulating device with an auxiliary valve which operates to close the regulating device at the desired pressure on the hoops.

2. In a cask hooping machine having pressure plates, a pressure regulating device having a piston, an auxiliary valve and weight plates for regulating the operation of the valve and piston according to the distance of the pressure plates from each other.

3. In a cask hooping machine having pressure plates, a pressure regulating device having a piston, an auxiliary valve and a series of weight plates suspended from the under pressure plate when the pressure plates are nearest each other and successively laid on a rod connected with the auxiliary valve while the pressure plates are returning to their initial position.

4. In a cask hooping machine, the combination of a pressure regulating device with an auxiliary valve which operates to close the regulating device at the desired pressure on the hoops, said operation on the regulating device being effected by the waste water from the auxiliary valve.

That I claim the foregoing as my invention, I have signed my name in presence of two witnesses, this 12th day of April 1915.

FRIEDRICH STROHL
